UNITED STATES PATENT OFFICE.

LAWRENCE HITCHCOCK, OF CLEVELAND HEIGHTS, OHIO.

GATE.

Application filed September 11, 1926. Serial No. 134,872.

My invention relates to improvements in gates, and more particularly to that class of structures adapted to be opened and closed by operating levers and the mounting thereof and of the hinged gate member itself. The object of my invention is the provision of an extremely simple, cheap and efficient structure of this class, possessing strength, with a minimum of parts and certainty of 10 operation and maintenance of closure, as desired.

All structures of this class with which I am acquainted not only rely upon latching mechanism for maintaining the closure of 15 the gate, when desired, but separate external mounting mechanism ordinarily is contemplated for the actuating means, both for the gate and its latch.

It has been my endeavor, accordingly, 20 materially to simplify the actuating means, while so mounting the swinging gate as to obviate the requirement of any latch. Thus, my improved gate structure preferably is 25 swung from one post, which also serves to support from its upper portion the necessary actuating mechanism, while the opposite gate post is so spaced as to permit the gate to bear against it directly when in closed 30 position, while a portion of the actuating means serves to maintain said gate temporarily locked in this abutting position. The 35 features of my improvement may best be described in connection with the accompanying drawings, wherein:

Figure 1, is a perspective view of the structure showing the gate and its associated members in closed position.

Fig. 2, is a plan view thereof.

Fig. 3, is a fragmentary view of the gate 40 actuating mechanism; the members thereof being in the positions assumed for locking the gate while closed, and

Fig. 4, is a similar view thereof showing the members in the positions assumed for 45 locking the gate while open.

Throughout the several figures of the drawings I have employed the same character of reference to indicate similar parts.

The gate *a* is stoutly hung by hinges *a'* to 50 swing upon the post *b* from its left side, and directly engage or abut against the post *c* when in its closed position.

The actuating mechanism per se for said gate is shown in Figs. 3 and 4 in the two 55 operative positions thereof; the same being pivoted from the top of a short post *d* which

also acts as a stop for the gate in its open position. The several members comprise two pivoted arms *e* terminally connected with the bent arm *f*, attached by an eye-bolt *a''* 60 intermediately of the gate. Two depending weights *g* and a loop *h* are connected at the knee-joint thus formed by the pivotal bolt *e'*.

Secured at the top of the post *b* is a bracket *b'* which braces the diagonals *i*, *i*, 65 likewise secured near the upper portion of said post. The operating levers *j*, *j*, having cords *j'*, and *j''*, are intermittently fulcrumed at the upper ends of the diagonals by means of bolts *j''', j'''*, while connecting wires *h', h''* 70 unite the inner ends of said levers with the loop *h*, and thereby, with the actuating mechanism or knee-joint.

Since the knee-joint is intermediately weighted and its construction permits it to 75 throw slightly past the horizontal with the free end of the bent arm *f* engaging the stop *f'*, as shown in Figs. 1 and 3, it is seen that the gate is normally locked in closed position, from which neither pressure nor 80 winds directed from either side of the gate can dislodge it. It is braced from opening by the weighted knee-joint, while it is prevented from swinging further by its engagement with a face of the post *c*. 85

When, however, it is desired to open the gate, a sharp pull upon either of the ropes or cords *j'* will cause the corresponding operating lever *j* to throw the knee-joint members rearwardly of the pivotal post *d*, with the 90 gate bearing against said post as a stop, in its fully open position, as indicated in Fig. 4. As before, the gate is held against swinging movement or closure by the weighted knee-joint in engagement with pivotal post 95 *d* until it is again actuated by one of the connected operating levers. This is of considerable advantage in practice for the reason that the gate and its attachments, which necessarily are loosely connected, nevertheless are withheld from wear, movement or rattling in stormy weather, either in the closed or open positions.

From the foregoing it will be appreciated that my improved gate mounting requires a 105 minimum of additional parts, as compared with the ordinary gate construction. One of the gate posts supports the operating levers extending at a distance upon both sides of the gate, while the other post serves as a 110 stop against which the gate closes. The short pivotal post for the actuating members

is availed of for the stop when the gate is in its open position, while no latch mechanism is required.

The improved construction herein disclosed comprises but few, simple and efficient parts, contributing to cheapness and avoiding liability to getting out of order or breakage. The operating means are positioned approximately at a forty-five degree (45°) angle with the gate, wherein the knee-joint may be most efficiently operated to open and close that member, meanwhile locking it in either alternative position. The mounting of both actuating levers directly upon one of the gate posts avoids the provision of supporting structures at a distance from the gate.

The operating means, and particularly the knee-joint mechanism, comprise the pivoted metallic members *e* and *f* carried by the short post *d* and hinged intermediately of the gate by means of a simple eye-bolt *a'*, which may be opened to accommodate the end of member *f*, slipped through an opening therein, and closed to form a simple and cheap loose connection for swinging and locking the gate in its different positions.

Having now described the improved gate structure of my invention, I claim as new and desire to secure by Letters Patent, the following:

1. In a structure of the class described, the combination with two spaced gate posts, of a gate hinged from one of said posts and free to swing into and out of engagement with the other post, operating mechanism there-

for, comprising pivoted flat metallic members united as a knee-joint, an eye-bolt connection between one of said members and the gate, a pivotal stop post for said knee-joint, actuating levers pivotally mounted at the upper end of the gate-hinging post respectively extending on both sides of said gate, and means connecting the levers intermediately of said knee-joint adapted to actuate it and the gate into alternative locked positions of the latter in engagement with the outer gate post or with the pivotal stop, substantially as set forth. 40

2. In a structure of the class described, the combination with two spaced gate posts, of a gate hinged from one of said posts and free normally to swing into and out of engagement with the other of said posts, weighted knee-joint mechanism connected intermediately of said gate, including a pivoted angular member and stop adapted to be thrown out of alignment with its coacting pivotal member, a pivotal post for said knee-joint positioned to be positively engaged by the gate in its open position when locked by the knee-joint, Y-supports upon the gate-hinging post, actuating levers pivotally mounted thereon and extending on both sides of said gate, and means respectively connecting said levers intermediately with the knee-joint mechanism for actuating it and the gate into rigidly locked open and closed positions, substantially as set forth. 50

In testimony whereof I do now affix my signature. 55

LAWRENCE HITCHCOCK. 60
